UNITED STATES PATENT OFFICE.

DOMINICK RODGERS, OF PITTSBURGH, PENNSYLVANIA.

FAN.

Application filed May 17, 1924. Serial No. 714,174.

The present invention relates to rotary fans of the ventilating type, comprises the same subject matter as the abandoned application for Patent Serial No. 526,361, filed December 31, 1921, by the present inventor, and has more particularly to do with the matter of increasing the field covered by the air discharged from the fan, said object being accomplished without the usual alternate or rotary movement of the motor, as will be more fully explained hereinafter. The means used to accomplish the above mentioned result consists in the use of fans provided with inwardly turned vanes, said vanes being connected to each other, and angularly disposed with reference to planes coincident with, and perpendicular to the axis of rotation of the fans themselves, as will be more clearly set out below.

In the usual ceiling fan as found in practical use in theaters, and other public places, the motor is often in a spherical form, and while the fans revolve continuously discharging the air from the fan, the motor itself revolves continuously, performing a complete revolution about its own axis. In the case of the present invention, a practically universal field of air discharge is formed by means of the fan blades, without such a movement of the motor.

In a modification I have also shown a type of single blade fan which accomplishes a greater distribution of air without the alternate arcuate movement commonly used with ventilating table fans in common use.

Another feature of the present invention relates to a specially arranged means for setting the fan in various positions; and still other features relate to a means for simply connecting the fan blades used to each other, same presenting an advantageous feature of construction, both of said features being further elaborated upon in the specification.

In the accompanying drawings I have shown one complete example of the physical embodiment of my invention, and a modification, constructed according to the best mode I have so far devised for the practical application of the principles of my invention.

In the drawings, Figure 1 is a side elevation of my improved fan.

Figure 2 is a front elevation of Figure 1 taken from the left of same.

Figure 3 is a side elevation of a modified form of my invention designed to supplant the ordinary "table variety" of ventilating fan.

Figure 4 is a type of my fan as applied to a ceiling.

Figures 5 and 6 are diagrammatic views for the purpose of illustrating the angular positions of the vanes of my invention.

Figure 7 is a view looking upward of an ordinary ceiling fan.

Figure 8 is a detail front view of the means used in attaching the blades of my fan to each other.

Figure 9 is a vertical section of Figure 8 on line 9—9.

Figure 10 is a detail front view of a locking means used in connection with my invention.

Figure 11 is a side view of Figure 10.

In the drawings the numeral 1 indicates a fan constituting my invention, having the base 2, a stem 3, and within which is the pintle 4. Surrounding the pintle 4, is the pipe 5, on the upper end of which is mounted the motor 6, the latter carrying on its shafts 7, 8 the fan blades 9, 10, and 11, 12 respectively. It is seen that the fan blades just mentioned each have a plurality of inwardly turned vanes, disposed angularly with reference to each other. The vanes are numbered 13, 14, and 17, each blade is also provided with the usual perpendicular vane represented by numeral 17.

These vanes 13, 14, and 17 are connected to each other on each fan blade in order to make up a complete blade as is readily understood. The vanes 17, 17 are perpendicular to a plane which is parallel to the axis of rotation of the blades as seen from Figures 1 and 5 of the drawings, in which 24 is the axis of rotation, and 23 a plane perpendicular thereto.

These vanes 17, 17 have a flat or cutting portion 19, and a flared portion 20 as is usual and common to most fans of the type.

under consideration. The vanes 13, 14, have similar flat portions 21 and flared portions 22 as shown, and are angularly disposed with reference to the plane 23 which is perpendicular to the axis of rotation 24, as shown in Figure 5, said figure corresponding diagrammatically to Figure 1 of the drawing. It is further evident that said vanes 13, 14, are also angularly disposed with reference to a plane 25, which is coincident with the axis of rotation 24, as shown diagrammatically in Figure 6, which corresponds to Figure 2. It is seen that the lower half portion of the fan blade 9 shown in Figures 1 and 2 is indicated by the vanes 13, 14 and 17 of Figures 5 and 6. The Figures 1 and 2 also very clearly illustrate the angular disposition of the said vanes 13, 14, with reference to both planes 23 and 25 just described.

The purpose of having the vanes of the fan blades 9, 10, 11, 12, constructed as described is of course to increase greatly the field of action of air distribution, without using hardly any increase of power. The arrows of Figure 1 and Figure 4 indicate the direction of discharge of air from the fans, and an almost universal field of delivery is provided by my invention, and without body motion of the motor 26, as is usually done with ceiling fans of the type shown in Figure 7 in which the arrow indicates the revolution of the motor 26 carrying the usual fan blades 27, 27.

The discharge of air from a fan such as 28 just described is moreover merely in a single direction which is parallel with the axis of rotation of the fan blades 27, 27, while the present invention as shown by Figure 4 produces a practically universal field of air discharge without the revolution of the motor 29. Again in connection with the type of fan shown in Figure 3, same practically accomplishes as good an air delivery as the ordinary alternate motion fan which is thrown from side to side, and so well known; and this is accomplished by the present invention without movement of the motor 29. The fan blades 9, 10 and 11, 12 are fastened to each other as shown in Figures 8 and 9 in detail, the blade 9 is cut at 30, 30, and the end 31 is returned upon the other companion blade 10 as shown; while the blade 10, is similarly cut at 32, 32, and the ends 33, 33, returned upon the blade 9 in a reverse direction. This method of securing each pair of blades together has proven very simple and efficient for the purpose in hand.

The base 2 before mentioned has an upward extension 34 on which is mounted a union-like part 35 provided with a shoulder 36, and as shown in Figures 10, 11, the pipe 5 which revolves on pintle 4 finds an abutment against said shoulder 36. Pref-

erably mounted pivotally at 37 in the part 35 is the locking lever 38 which is adapted to engage in a series of slots 39, 40, etc. formed in the end of the pipe 5. The said locking lever may be frictionally held in position, or any well known equivalent means may be used to hold it in either of the positions 41, or 42. It is evident from the above that the motor 6 may be moved around on the pintle 4 by merely disengaging the lever 38, and placing same in another of the slots 40, 41, etc. as desired, thus diverting the field of air discharge in any preferred direction. This is a more important feature in the type of fan shown in Figure 3 which is a modification of the fan of Figures 1 and 2, in which an inclined pintle 43 is used, though a vertical one may also be used with the single fan type of the present invention.

I claim:—

1. In a device of the character described, a plurality of fan blades, each having a number of vanes provided with a flat and a flaring portion, and said vanes being angularly disposed with reference to planes parallel with, and perpendicular to, the axis of rotation.

2. In a rotary fan, a pair of revoluble fans mounted in opposed relation to each other, each composed of a series of vanes disposed in various angular relations with respect to planes parallel with, and at right angles to, the axis of rotation; a supporting base having a pintle formed thereon, a pipe revolubly carried on the pintle, a plurality of slots in the revoluble pipe, and a lock lever pivotally mounted in the supporting base, adapted to lockingly engage the complementary slots of the said pipe, and prevent revolution of the fans about the fan base.

3. In a rotary fan, a fan blade having a vane in a plane perpendicular to its axis of rotation, and a plurality of vanes each having a flat and a flaring portion formed thereon, and angularly disposed with reference to planes parallel with, and perpendicular to, the axis of rotation.

4. In a rotary fan, a pair of opposed fans, each composed of a number of blades, the vanes of which each have a flat and a flaring portion, and are disposed in a plurality of angular relations with reference to the axis of rotation, and each blade having a vane perpendicular to the axis of rotation.

5. In a rotary fan a pair of opposed fans, each composed of a number of vanes having a flat and a flaring portion formed thereon, said vanes being disposed in a plurality of angular relations with reference to the axis of rotation.

6. In a fan, a number of fan blades, each provided with a number of vanes having a flat and a flaring portion, and angularly dis-

posed with reference to planes parallel with and perpendicular to, the axis of rotation; in combination with a supporting base having a shoulder formed thereon, a pintle 5 mounted in said base, a pipe revolvably mounted on said pintle and engaging said shoulder, a number of slots in the end of the

revoluble pipe, and a locking lever pivotally mounted in the base, adapted to engage the complementary slots in said pipe to prevent 10 revolution of the motor and fan blades about the aforesaid pintle.

In testimony whereof I affix my signature.
DOMINICK RODGERS.
